CONDUCTOR PROTECTING TAP CLAMP

Ralph R. Pittman and Carroll H. Walsh, Pine Bluff, Ark.

Application January 22, 1937, Serial No. 121,812

4 Claims. (Cl. 173—273)

This invention relates to clamps for use in tapping electrical conductors, particularly to the type of clamp known as live line clamps.

Clamps of this type are well known and extensively used. Since several types of metals are used as electrical conductors, it has heretofore been common practice to use clamps either of the same material as the conductor, or those in which the portion engaging the conductor is either of the same material, or of such material that galvanic or electrolytic action due to the dissimilar metals will be so small as to have a negligible practical effect on the conductor. This practice requires a different clamp for each conductor material.

It is an object of the present invention to provide means for using one type of clamp for all conductor metals.

Also, it is present practice to removably attach the clamp directly to the conductor, and under such a condition the conductor may be damaged by arcing, burning and pitting, or its tensile strength lowered by annealing.

It is an object of the present invention to provide means whereby the conductor cannot be damaged by arcing which occurs when a load is connected or disconnected from a conductor due to the attaching or removing of the live line clamp.

More specifically, it is an object of the invention to provide, in combination with a live line clamp, a conductor protecting member or sleeve which is removably attached to the clamp, means for permanently attaching the protecting sleeve to the conductor in response to the tightening of the clamp, and means for removing the clamp from the protecting sleeve following its application to the conductor as described.

Another object is to provide a bimetallic sleeve as above described in which the metal portions of the member which are respectively in physical and electrical contact with the clamp and the conductor are electrically compatible with the metals of the latter members.

With these and such other objects in view as may later appear, our invention resides in the novel form, arrangement and combination of the parts forming the device.

In the drawing (1 sheet): Fig. 1 illustrates a side elevational view of the device just prior to its application to a conductor; Fig. 2 illustrates the device following its application to the conductor; Fig. 3 is a fragmentary sectional view taken along the line III—III in Fig. 1; Figs. 4 and 5 are respectively front and side elevational views of the conductor protecting member; and Fig. 6 shows the appearance of the conductor protecting member following the removal of the clamp.

Referring in detail to the drawing, the live line

clamp shown in Figs. 1 and 2 includes the body portion 11, having the inverted V-shaped portion 19 arranged to cooperate with the shoe 14, between which an object may be clamped through the rotation of the screw eye 13. For convenience 5 in applying the clamp to energized conductors, the upper end of the clamp is provided with the eye 12. A tap wire 15 is attached in any suitable manner to the body portion 11.

At a point along the line of movement of the 10 shoe 14, a pair of inwardly extending slots 18 are provided. These slots are arranged for supporting on the clamp the conductor protecting member 16, shown more in detail in Figs. 3, 4, and 5. The conductor protecting member 16 is formed 15 from a flat ductile metal strip, being bent over at its upper end to fit in the V-shaped portion 19 of the clamp, and at its lower end to conform to the inner portion of the upper surface of the shoe 14. For mounting the conductor protecting member 20 on the clamp, a pair of spaced projecting portions 17 of the member, cut and bent outwardly therefrom, are arranged to extend through the slots 18 of the body portion of the clamp. To insure retention of the conductor protecting member 25 in place on the clamp, the outermost ends of the portions 17 may be bent either downwardly or upwardly with respect to the body portion of the clamp.

With the conductor protecting member in position on the clamp as just described, it may be applied to the conductor 10 in the position illustrated in Fig. 1 by means of insulated or live line sticks. The screw eye 13 is then rotated by means of a suitable insulated tool in a direction 30 to move the shoe 14 upwardly toward the conductor 10. In so doing, the inner upper surface of the shoe first engages the outwardly bent lower portion of the conductor protecting member 16, and as the movement of the shoe is continued, 35 the conductor protecting member 16 is wrapped around the conductor, finally assuming the position illustrated in Figs. 2 and 6. As the shoe 14 passes the projections 17, the latter are sheared off between the shoe and the body portion of the 40 clamp.

After the elements have taken the position shown by Fig. 2 following the application of the clamp, the latter may now be repeatedly removed and applied without further disturbing the conductor protecting member 16, the latter remaining 45 permanently on the conductor in the position shown by Fig. 6. It will be seen that any arcing or metal burning incident to the electrical connection of the tap wire 15 to the line conductor 50 19 will occur on the outside surface of the conductor protecting member, and not on the conductor. Any arcing on the conductor is highly undesirable, since it is normally under tension, and may not only be weakened by the burning 55 60

away or pitting of the metal, but also by annealing and thus weakening its tensile strength.

The above described arrangement solves the problem of damage to the conductor, regardless 5 of the material of the conductor, clamp, or protecting member, and in this manner one of the objects of the invention is accomplished.

The solution to the problem of preventing damage to the conductor through arcing is an important 10 object of the invention, but still another problem is solved by our invention.

The conductor protecting member 16 may be made of a bimetallic strip, and is so indicated in Fig. 5 of the drawing, but it is clear that it is not necessarily bimetallic to solve the conductor burning problem, and the present invention therefore embraces a protecting member of either a single metal, or a bimetallic member.

The conductor protecting member is bimetallic 20 only in the event that the material of the conductor is electrically incompatible with respect to that of the clamp. For the purpose of this invention, metals are "electrically incompatible", "electrolytically incompatible" or "incompatible" 25 if, when placed in abutting physical contact and carrying an electrical current under any atmospheric conditions, sufficient galvanic or electrolytic action occurs to damage either or both metals. For example, copper and aluminum are 30 well known incompatible metals, and an aluminum conductor clamped in a copper clamp and completing an electrical circuit will in a short time seriously damage both. On the other hand, high copper brasses or bronzes are compatible 35 with copper, and consequently these materials are widely used in the manufacture of live line clamps. Again, zinc and copper are incompatible, therefore a clamp suited for copper conductors is unsuited for either an aluminum or a galvanized iron conductor.

These conditions of incompatibility have heretofore been recognized, and have been met by the use of a different clamp for use on aluminum, galvanized iron, and copper conductors, in each 45 of which the conductor engaging portion is of a metal compatible with the metal of the conductor. Since all of the above conductor materials have definite economical applications in electrical utility construction, it has heretofore been necessary for each utility to carry quantities of each 50 style of clamps in stock. Obviously their investment would be greatly reduced, and their operations simplified, if one clamp could be adapted for all conductors, and this is another object of the present invention.

To illustrate specifically our solution to this problem, we may assume that it is desired to have available only high copper content clamps, which in themselves are suited only for copper conductors. It is now desirable to connect a tap to an 60 aluminum conductor. In this event, the conductor protecting member 16 will be bimetallic; that is, copper on the outside, and aluminum on the inside, so that, when the adjustable means of the clamp is moved in a direction to clamp the protecting member between the conductor and the clamp, only compatible metal surfaces will be in contact. It is obvious that the conductor protecting members are extremely low in cost as 65 compared to the cost of the entire clamp, and since they are interchangeable on the clamp, a very considerable saving is effected.

It should be understood that the two metals forming the conductor protecting members are so united as to effectively exclude atmospheric moisture, and that therefore no electrolytic action can occur within the members themselves. 5

From the above description it will be clear that the problem of preventing damage to the conductor from arcing is solved regardless of the nature of the metals involved; also that both this problem and that of preventing damage from electrolytic action is solved through the use of a suitable conductor protecting member. 10

While we have used quite specific language in describing our invention herein, this has been done for the purpose of facilitating an understanding of the construction involved, and our invention is to be limited only as is necessitated by the claims and the prior art. 15

We claim, as our invention:

1. In a live line clamp having rotatively moving 20 adjustable means for engaging a conductor, a conductor protecting member, means for detachably mounting said member on said clamp, means responsive to the rotary movement of said adjustable means in one direction for affixing 25 said protecting member to the conductor between the latter and said clamp, and means responsive to rotary movement of said adjustable means in the other direction for disengaging said clamp from its clamped position with respect to said 30 conductor protecting member.

2. In combination, a conductor, a metal clamp having adjustable clamping means for engaging said conductor, said clamp having a conductor engaging portion of a metal electrolytically incompatible with the material of said conductor, a bimetallic protecting member detachably mounted on the body portion of said clamp, said bimetallic member having conductor and clamp abutting surfaces of metals respectively compatible with 40 the material of said conductor and said clamp, and means responsive to movement of said adjustable means for releasing said bimetallic member from the body portion of said clamp, said movement affixing and clamping said protecting member to the conductor in interposed relation to said clamp and said conductor so that only metal surfaces compatible respectively with the material 45 of the conductor and the clamp are in physical contact therewith.

3. The combination with a live line clamp having adjustable clamping means for removably engaging a conductor, a protecting member detachably mounted on the body portion of said clamp, and means responsive to movement of said adjustable means for releasing said member from the body portion of said clamp, said movement affixing said protecting member to the conductor in interposed relation to said clamp and said conductor. 55

4. The combination with a live line clamp having adjustable clamping means for removably engaging a line conductor, of a protecting member detachably mounted on the body portion of said clamp, and means responsive to movement of said adjustable means for releasing said member from the body portion of said clamp, said movement permanently attaching said protecting member to the conductor and clamping said member between said conductor and said clamp. 65
